William Jackson & Nathan H. Jackson, New York.
Letters Patent (Design No 44) Dated January 4th 1846.

The schedule referred to in these Letters Patent and making
part of the same.

To all whom it may concern. Be it known that we William
Jackson and Nathan H. Jackson of the City County and State of
New York have invented or produced a new design for a "fire place
grate" and they do hereby declare that the following is a full

22
and each description of the same, reference being had to the annexed drawings making a part of this specification.

Our grate consists of three parts, a frame of grate a centre or summer piece, and a fender or front piece these are all constructed in Shell, scroll, leafage and lace imitation work and after the style of Architectural ornament of Louis fifteenth, the whole making up a uniform "fire place grate" of that style of architecture.

The frame of grate, is a central piece of S. shell and leafage work which unites the scrolls b.b on top of said frame directly under this is a piece of S. shell and leafage work making a centre to the frame of grate see C.C. in drawing, below this is a S. shell forming the centre of the inner part of said frame and may be known as d in the drawings and unites with the scrolls E.E. - g,g are pieces of S. shell and leafage which unite with b.b. and f.f. scrolls h,h are plain corner pieces of scrolls and inlaid with a diamond matting, i.i. are pieces of shell work and uniting the scrolls f.f. to k,k, these last being circular scrolls - l,l. are open wreaths of flowers dropping from f.f. to the scrolls and shell pieces from the corners known as m.m. and n.n. these last being scrolls uniting with the S. shell and leafage pieces known as o.o. - p,p are scrolls with ornaments in leafage and unite with the S. shell pieces S.S. - these last unite with the base terminus pieces consisting of scroll shell and leafage work and may be known as r.r. by the scrolls t.t. the base disappears in scrolls behind the fender; v.v. are scrolls with a shell in the centre and unite with the shell and leafage pieces w.w. which connect with the scrolls v.v. and by the shells below to the scrolls x.x. which terminate by uniting with r.r. - thus it will be seen that the above is finished on the inside by a continuous line of shells evaporating upon the matting a lace work of the ground, of which especial mention will be made in another part of this specification, on each side of the grate this is relieved by a light double united scroll with diamond centre work.

which will be known as 3.3.

The centre or Summer Piece. This is a piece used in the place of the fire grate in summer, and is quite ornamental - it slides or is placed at the back of the before mentioned "frame of grate." This is built upon a curved line of pillars or columns for a foundation above which is a piece of scroll work to fill in and a base in perspective of the matting or lace work.

This is the ground work of a continued or deepened such in which may be placed a painting or figure of statuary at pleasure this surrounded by a run of light scrolls and the sides thereof are light scrolls with diamond centres and are raised up out of the lace net work - on the outside over the pillars are placed vases of woven flowers also raised out of the net work and still outside of these are continuous scrolls from the sides of the outer pillars continuing the whole way round to the close at top where they unite in a termination - directly under this an urn of flowers, this urn being formed of shells and scrolls resting ^{upon} a centre circle of shells with side scrolls raised out of the ground matting or lace work, this is also crowned by scrolls upon which rest two birds right and left facing each other these being of Grecian architectural ornament.

The Tender. Consists of a beautiful relieved piece of scroll shell and leafage with urn of flowers and scrolls extending on each side the whole being known as A in the drawing - B.B. in the drawings is a continuous run of scroll and shell work terminating on the ^{two} side feet, which will be known as scroll and shell ornament by C.C. in the drawings - The lower line of scrolls unite with this ^{and} extend and unite ^{with} the centre piece A, this line of scrolls rise up from the matting of lace ^{work} which is further relieved in its central part by a light scroll filled in ^{with} the diamond work as stated in the other part - or "frame of grate"

The Lace ground work or matting. - This is a new thing

Des. 44

to be introduced upon cast iron, though the same thing has been produced in composition, though we have no knowledge of its being cast in metal before our own introduction and we feel sure we are the first to produce it upon metal although we only claim it as here used upon grates.

What we claim as our production in the herein specifications and drawings is the arrangements of the figures upon the castings, making up the three parts of a "Fire place grate" viz: - a frame of Grate, a Summer piece, and a Tender, as shown and described, the same consisting of Scroll, Shell and Leafage work, in the Architectural order of Louis the XV.

We also claim the herein shown pattern of "lace ground work" or matting, as applied to, or cast upon, or in, iron for the purpose of ornamenting, Grates, and such like castings, or work.
